UNITED STATES PATENT OFFICE

1,966,921

CENTRIFUGAL EXTRACTOR

Fred A. Conterman, Syracuse, N. Y., assignor to
Easy Washing Machine Corporation, Syracuse,
N. Y., a corporation of Delaware

Original application January 5, 1931, Serial No.
506,606. Divided and this application June 27,
1931, Serial No. 547,368

8 Claims. (Cl. 210—63)

This invention relates to a new and improved centrifugal extractor and one which is particularly well adapted for use in extracting liquid from clothes which are being washed.

This application is a division of my co-pending application for Centrifugal extractor, filed January 5, 1931, Serial No. 506,606.

The main object of my invention is to provide a device of this character in which the means for locking the cover of the extractor in the closed position is carried on the cover itself.

Other objects and advantages relate to the details of the construction and to the form, relation and arrangement of parts by which the above objects are accomplished, all as will more fully appear from the following description taken in connection with the accompanying drawings in which:—

Figure 1 is a top plan view, partially broken away, of an apparatus embodying my device.

Figure 2 is a section on line 2—2 of Figure 1.

Figure 3 is a section on line 3—3 of Figure 4.

Figure 4 is a section on line 4—4 of Figure 3.

Figure 5 is a section on line 5—5 of Figure 3.

Figure 6 is a section on line 6—6 of Figure 1.

Figure 7 is a section on line 7—7 of Figure 6.

My device comprises a main frame 1 supported on appropriate legs not shown.

Frame 1 has a centrally disposed internally threaded depending boss 2. To the under side of main frame 1 is secured a gear housing 3. A skirted cover member 4 is positioned on the top of frame 1.

A main vat 5 is positioned on top of member 4 with a gasket 6 interposed therebetween. A tubular supporting member 7 extends downwardly through vat 5 and member 4 and is threaded in boss 2 on frame 1 to lock such parts together.

A vertical shaft 8 has its lower end journaled in a depending boss 9 in the lower end of gear housing 3, a thrust ball 10 being interposed between the lower end of shaft 8 and the bottom of boss 9.

The upper end of shaft 8 is journaled in supporting member 7 and extends upwardly therethrough.

For the purpose of sealing the upper bearing of shaft 8 against liquid extracted from the clothes, I provide a packing gland 11 on the upper end of member 7 secured in position by a collar 12 threaded on the upper end of member 7.

On the lower end of collar 12 is provided an annular flange 13. On the upper end of shaft 8 is positioned a supporting member 14, the upper end of shaft 8 being square and entering a

square hole in supporting member 14 so that they may rotate together.

Member 14 has a depending annular skirt 15 which extends beneath flange 13 on member 12 and in spaced relation thereto. The upper end of member 14 is preferably hexagonal in shape.

The foraminous extractor basket 16 has in its bottom an hexagonal recess 17 in which the upper end of member 14 is received so that the rotation of member 14 will cause the rotation of basket 16.

On the upper end of vat 5, I provide a hinged cover 18 having journaled on the under side thereof a rotatable member 19 adapted to frictionally engage the upper end of basket 16 to function as a cover therefor, and also as a guide when basket 16 is rotating.

On the lower end of shaft 8 and secured thereto as by a set screw 20 is a retaining collar 21. Above collar 21 and supported thereon is a male clutch member 22 rotatable on shaft 8.

On the lower end of member 22 and secured thereto as by a pin 23 is a worm gear 24 in mesh with a worm 25 which is secured to a shaft 26 which shaft 26 is in turn secured to the armature shaft of a motor not shown.

A female clutch member 27 is slidably mounted on shaft 8 above clutch member 22 and is held against relative rotary motion with respect to shaft 8 by a key 28.

Encircling shaft 8 is a spiral spring 29 having its lower end abutting against clutch member 27 and having its upper end abutting against a collar 30 which is secured to shaft 8 as by a set screw 31.

The tension of spring 29 is such that it normally urges clutch member 27 downwardly into clutching engagement with clutch member 22. On the upper end of clutch member 27 is secured as by a split ring 31', a circular disk 32 having on its under face a brake lining 33.

Beneath brake lining 33 and encircling clutch member 27 is an annular disk 34.

In one side of gear casing 3 is slidably mounted a vertical shaft 35 carrying a yoke 36 which encircles clutch member 27 and is adapted to contact with member 34 so that the upward movement of shaft 35 carrying with it yoke 36 will cause member 34 to contact with brake lining 33 and carry upwardly clutch member 27 out of clutching engagement with clutch member 22, the frictional contact between member 34 and brake lining 33 aiding to bring shaft 8 to rest.

The upper end of shaft 35 is provided with a plurality of rack teeth in mesh with gear teeth

37 provided on one end of a horizontal rock shaft 38 journaled in gear casing 3.

On the outer end of the shaft 38 is provided a crank arm 39 connected as by a link 40 to one end of a crank 41, the other end of crank 41 being pivotally mounted on main frame 1.

A vertical shaft 42 has its lower end journaled in main frame 1 and extends downwardly therethrough.

10 On the lower end of shaft 42 is provided a crank arm 43 connected as by a link 44 to crank 41. The upper end of rock shaft 42 is journaled in a flange 43 secured to the upper end of vat 5.

Beneath flange 43, an operating lever 44 is secured as by a pin 45 to rock shaft 42. The rocking of shaft 42 will through crank arm 43, link 44, crank 41, link 40 and crank arm 39, cause the rocking of shaft 38 and this, in turn, will cause vertical shaft 35 to be raised or lowered as desired to de-clutch members 27 and 22 or move them to the clutching position.

On the upper end of shaft 42 is secured a gear 46 in mesh with rack teeth on a slidable pin 47. Pin 47 is slidably mounted in flange 43 and may be moved inwardly beyond the inner end of flange 43, but may be moved outwardly only to the outer edge thereof, a stop 48 being provided to limit the outward movement of pin 47.

On the under surface of cover 18 are provided 30 opposed spaced tubular lugs 49 and 50. A shaft 51 is slidably mounted in lugs 49 and 50 and is of such a length that when properly positioned, it will extend from the outer end of lug 49 to the outer end of lug 50.

35 The aperture in lug 49 is in alignment with the aperture in the flange 43 in which the rod or pin 47 is positioned so that when rock shaft 42 is rocked to move clutch members 27 and 22 into clutching relationship to cause the rotation of basket 16, rod 47 will be moved inwardly into the aperture in lug 49 to lock the cover 18 in the closed position.

40 When this movement of rod 47 takes place, it will contact with rod 51 to move the same axially and to move the opposite end out beyond the outer end of lug 50.

45 Adjacent the outer end of lug 50 and on flange 43 is provided a tubular boss 52 in registration with the aperture in lug 50 so that when rod 51 moves outwardly beyond the outer end of lug 50, it will enter the aperture in boss 52 and become an additional means for locking cover 18 in the closed position.

50 At approximately the center point of rod 51, I provide a plurality of rack teeth 53 in mesh with a segmental gear 54 which is secured to the lower end of a vertical rock shaft 55 which is journaled in cover 18.

To the upper end of rock shaft 55 is secured 60 an operating lever 56 by means of which segmental gear 54 may cause the axial movement of the rod 51.

65 When rock shaft 42 is in the position to hold clutch members 27 and 22 out of clutching engagement, the rod or pin 47 will be fully retracted in flange 43 abutting against the stop member 48.

70 When the rod 47 is in this position and the lever 56 has been manipulated to withdraw rod 51 from boss 52 the cover 18 may be opened.

75 It is desirable, if not absolutely essential, that means be provided to make it impossible for rock shaft 42 to be manipulated when the cover 18 is open and to accomplish this result, I provide in flange 43 adjacent rod 47 a vertically extend-

ing spring-pressed pin 56' having an upper end 57 comparatively small in diameter and a lower tubular end 58.

A spiral spring 59 is positioned in the lower end 58, abutting against flange 43 and normally tends to move member 56' upwardly to the top of the aperture 60 in which it is positioned. 80

At approximately the middle point of pin 47, I provide a notch 61. The relation of parts is such that when the pin 47 is in the fully retracted position, the notch 61 will be in registration with member 56' and member 56' will move upwardly to bring its enlarged lower end 58 into registration with the notch 61 in pin 47 so that such pin 47 can not be moved axially. 85

When the parts are in this position, the upper end 57 of member 56' which is of such a diameter as to be out of the path of movement of pin 47, will extend upwardly above the flange 43. 90

When the cover 18 is returned to the closed position, it will contact with the upper end 57 of the member 56' and will move such member 56' downwardly against the action of the spring 59 to carry the enlarged lower end 58 of member 56' out of registration with pin 47 so that the same may be moved axially. 95

When the cover is in the locked position with the pin 47 positioned in the aperture in the lug 49 in which position of parts the basket 16 is rotating, and it is desired to open the cover 18, 100 the lever 56 may be manipulated to cause rod 51 to move axially to withdraw the end of rod 51 from the aperture in lug 52. This movement of rod 51 will cause rod 47 to be pushed out from the aperture in lug 49 to fully unlock the 110 cover 18. This movement of rod 47 will, through gear 46, cause shaft 42 to be rocked to move members 27 and 22 out of clutching engagement so that the basket 16 will come to rest.

This relation of parts permits the unlocking 115 of cover 18 and the stopping of basket 16 to be accomplished by the manipulation of only the lever 56 without the necessity of also manually manipulating the lever 44.

Similarly, when the cover is closed and the 120 lever 44 is manipulated to start rotation of basket 16, rod 47 will automatically enter the aperture in lug 49 carrying before it rod 51 and moving the same into registration with the aperture in lug 52 so that the starting of basket 16 by 125 manipulation of lever 44 will, at the same time, lock cover 18 in position without any necessity of manipulating lever 56.

It will be understood that my invention may be embodied in various forms and is not restricted 130 to the exact form, shape and relation of parts here disclosed, as various changes may be made without departing from the spirit of my invention, for although I have shown and described a specific structure and form and relation of parts 135 thereof as an embodiment of an exemplification of my invention, I do not desire to restrict myself to the exact size, shape or relation of parts as various changes may be made within the scope of the appended claims. 140

I claim:

1. In an extractor, a casing, a cover for said casing, means for holding said cover in a locked position comprising a longitudinally movable locking means, manually operated means for 145 moving said locking means in one direction to lock said cover on said casing, and separate manually operated means for moving said locking means in the opposite direction to unlock said cover. 150

2. In an extractor, a casing, a cover for said casing, means for holding said cover in a locked position comprising locking means secured to the underside of the cover, manually operated means for moving said locking means in one direction, said locking means upon movement engaging said casing, and separate manually operated means for moving said locking means in the opposite direction to unlock said cover.
- 10 3. In an extractor, a casing, a cover for said casing, means for holding said cover in a locked position comprising a longitudinally movable locking means carried on the underside of the cover, manually operated means for moving said locking means in one direction to lock the cover, separate manually operated means for moving said locking means in the opposite direction to unlock said cover, and means for locking said first-mentioned manually operated means when the cover is in an open position.
- 15 4. In an extractor, a casing, a cover for said casing, means for holding said cover in a locked position comprising a locking means secured to the underside of the cover, a movable member, manually operated means for moving said movable member to move said locking means in one direction to lock the cover, separate manually operated means for moving said locking means in the opposite direction to unlock said cover, and means comprising means engaged by said cover for locking said movable member with the cover in a closed position.
- 20 5. In an extractor, a casing, a cover for said casing, means for holding said cover in a locked position, a second locking means engageable with said first locking means, manually operated means for moving said first-mentioned locking means to unlocking position, said movement pushing said second locking means into unlocking position, and separate manually operated means for moving said second-mentioned locking means to locking position, said movement pushing said first-mentioned means into locking position.
- 25 6. In an extractor, a casing, a cover for said casing, means for holding said cover in a locked position, a second locking means engageable with said first locking means, manually operated means for moving said first-mentioned locking means to unlocking position, said movement pushing said second locking means into unlocking position, separate manually operated means for moving said second-mentioned locking means to locking position, said movement pushing said first-mentioned means into locking position, and means released by said cover when in a closed position for restraining movement of said second-mentioned locking means when the cover is open.
- 30 7. In an extractor, a casing, a cover for said casing, a movable member, a lock bar carried on the underside of the cover and movable into locking position with the casing on one side thereof and extending across the cover to engage said movable member, manually operated means for moving said movable member into locking position with the cover, said movable member incidentally moving said lock bar to locking position, and separate manually operable means for moving the lock bar and incidentally the movable member to unlocking position.
- 35 8. In an extractor, a casing, a cover for said casing, a movable member, a lock bar carried on the underside of the cover and movable into locking position with the casing on one side thereof and extending across the cover to engage said movable member, manually operated means for moving said movable member into locking position with the cover, said movable member incidentally moving said lock bar to locking position, separate manually operable means for moving the lock bar and incidentally the movable member to unlocking position, and spring-pressed means for locking said movable member against movement when the cover is open, said means being released by the cover when the cover is closed.
